UNITED STATES PATENT OFFICE

AARON W. HOWELL, OF CUMMING, IOWA

COLLAPSIBLE AWNING

Application filed August 24, 1931. Serial No. 558,990.

It is the general practice at the present time to employ as a sun shade for use on implements such as tractors the ordinary folding umbrella of relatively large size. 5 These are objectionable in that the central space under the umbrella is necessarily occupied by the umbrella standard which is connected with the tractor so that the operator of the tractor cannot occupy a position centrally beneath the umbrella.

The object of my invention is to provide a collapsible awning device of simple, durable and inexpensive construction and especially adapted for use on tractors or the like and in 15 which the upright supports for the awning are at the end, and the operator may occupy a space centrally below the awning.

More specifically it is my object to provide an awning of this kind in which the awning cover when in use is yieldingly held in taut condition and is firmly braced on all sides against either up or down movement caused by wind pressures.

My invention consists in the construction, 25 arrangement and combination of the various parts of the device, whereby the objects contemplated are attained, as hereinafter more fully set forth, pointed out in my claims, and illustrated in the accompanying drawing, in 30 which:

Figure 1 shows an end elevation of a collapsible awning embodying my invention in its extended position.

Figure 2 shows a similar view showing the 35 same collapsed.

Figure 3 shows a side elevation of my improved awning in an extended position, the awning cover being illustrated by dotted lines; and

Figure 4 shows an inverted plan view of my improved collapsible awning in its extended position, the dotted lines showing the position of the parts when the awning is collapsed.

Referring to the accompanying drawing, I have used the numeral 10 to indicate the main supporting bar, consisting of a straight horizontal central portion and upright end portions. These upright end portions may 50 be attached to a tractor or other support in

any ordinary manner, and this forms no part of my present invention.

The awning cover supporting mechanism at each end of the supporting bar is the same, and it will be necessary to describe only one of these mechanisms. Slidably mounted upon the supporting bar is a collar 11 having pivoted thereto two awning supporting ribs 12 normally extended laterally and toward the adjacent end of the supporting bar, but capable of folding up to position substantially parallel with the supporting bar, as shown by dotted lines in Figure 4.

To each of these ribs is pivoted a brace bar 13 near the central portion of the rib. This brace bar is extended downwardly, and the other end is pivotally connected to the adjacent upright portion of the supporting bar.

On each side of the awning I have provided a bar 14 pivoted to the outer end of both of the supporting ribs 12, and also to the outer end of each of the supporting ribs 12 is a flexible wire 15, the central portion of which is connected to the adjacent upright portion of the supporting bar. The awning cover, 75 which is made of flexible material, is connected at its side edges to the bars 14 and at its end edges to the wires 15.

Pivotedly attached to the collar 11 is a contractile coil spring 16, the outer end of which 80 is connected to a collar 17 slidably mounted upon the supporting bar and adjustably clamped in position on the supporting bar by a set screw 18.

In practical operation, and assuming that 85 the awning is in open position, it is obvious that the body portion of the awning will be tautly stretched over the awning frame because of the spring 16 applying a constant pressure tending to force the outer ends of 90 the ribs in a direction away from the main supporting bar, and by this means the awning cover is stretched in all directions outwardly. The two side edges of the awning are prevented from flapping in the wind by 95 means of the bars 14 to which they are connected, and the end edges are prevented from flapping in the wind by means of the wires 15.

These wires 15 perform the additional function of serving as braces to prevent up- 100

ward movement of the side edges of the awning cover, and they also support the ends of the awning cover that extend downwardly on the outer side of the upright portions of the 5 supporting bar.

When it is desired to collapse the awning, the operator simply grasps the two sliding collars 11 and moves them toward each other, whereupon the parts will assume the position 10 shown by dotted lines in Figure 4, with the bars 14, the ribs 12 and the braces 11 all substantially parallel with the sides of the supporting bar, and the awning may be held in this collapsed position by a strap or other 15 means tied around it.

In some instances it is desirable that when collapsing the cover, the tension of the spring 16 shall be released in order to make it easier to collapse it, and at the same time to relieve 20 the springs of tension, and this may be done by simply releasing the set screws 18, so that the springs and the collars 17 travel with the sliding collar 11.

I claim as my invention:

25 1. A collapsible awning frame comprising a supporting bar, a pair of ribs at each end of the supporting bar, each rib being pivotally and slidably mounted on the supporting bar, a brace pivoted to each rib and also to 30 the supporting bar, said ribs being swingable from a position substantially parallel with the supporting bar to a position inclined laterally and away from the adjacent end of the supporting bar, means for applying yielding pressure to the ends of said ribs that are pivoted to the supporting bar in a direction tending to move them toward the ends of the supporting bar, said frame adapted to support a flexible awning cover attached to the 35 outer ends of the said ribs.

2. A collapsible awning frame comprising a supporting bar, a pair of ribs at each end of the supporting bar, each rib being pivotally and slidably mounted on the supporting bar, a brace pivoted to each rib and also to the supporting bar, said ribs being swingable from a position substantially parallel with the supporting bar to a position inclined laterally and away from the adjacent 45 end of the supporting bar, means for applying yielding pressure to the ends of said ribs that are pivoted to the supporting bar in a direction tending to move them toward the ends of the supporting bar, a rigid bar on each side of the awning pivoted to the outer end of said ribs, said frame adapted to support a flexible awning cover attached to the outer end of the ribs and to said rigid bars.

3. A collapsible awning frame comprising a supporting bar, a pair of ribs at each end of the supporting bar, each rib being pivotally and slidably mounted on the supporting bar, a brace pivoted to each rib and also to the supporting bar, said ribs being 60 swingable from a position substantially par-

allel with the supporting bar to a position inclined laterally and away from the adjacent end of the supporting bar, means for applying yielding pressure to the ends of said ribs that are pivoted to the supporting bar in a direction tending to move them toward the ends of the supporting bar, a rigid bar on each side of the awning pivoted to the outer end of said ribs, said frame being adapted to support a flexible awning cover attached to the outer end of the ribs and to said rigid bars, and a flexible brace attached to a central portion of each of said ribs and extended inwardly and downwardly and attached to said supporting bar. 70 75 80

4. A collapsible awning frame comprising a supporting bar having a straight central portion and upright end portions, a collar slidably mounted on each end of the supporting bar, two ribs pivoted to each collar, a brace pivoted to each rib and extended downwardly and toward the supporting bar and pivoted thereto, a contractile coil spring attached to each collar, and means for adjustingly securing it to the supporting bar. 90

5. A collapsible awning frame comprising a supporting bar having a straight central portion and upright end portions, a collar slidably mounted on each end of the supporting bar, two ribs pivoted to each collar, a brace pivoted to each rib and extending downwardly and toward the upright portion of the supporting bar and pivoted thereto, and means for adjusting said collars longitudinally of the bar whereby the ribs may be swung from a position substantially parallel with the supporting bar to a position inclined laterally and away from the adjacent end of the supporting bar. 95 100 105
